DESIGN FOR A BUCKLE

Pearl F. Ashton, Providence, R. I., assignor to Ernest E. Weller, operating as E. E. Weller Co., Providence, R. I.

Application October 14, 1936, Serial No. 65,295

Term of patent 3½ years

To all whom it may concern:

Be it known that I, Pearl F. Ashton, a citizen of the United States of America, residing in 15 Belair Ave., Providence, county of Providence, and State of Rhode Island, have invented a new, original, and ornamental Design for a Buckle, of which the following is a specification, reference being had to the accompanying drawing, forming part thereof.

Fig. 1 is a front view of a buckle showing my new design.

Fig. 2 is a plan view of a buckle as shown in Fig. 1.

I claim:

The ornamental design for a buckle substantially as shown.

PEARL F. ASHTON.
